DESIGN FOR A CATBALL GAME DEVICE

Thomas R. Schlitz, Newark, N. J.

Application September 28, 1943, Serial No. 111,226

Term of patent 14 years

(Cl. D34—5)

To all whom it may concern:

Be it known that I, Thomas R. Schlitz, a citizen of the United States, residing at Newark, in the county of Essex and State of New Jersey, have invented a new, original, and ornamental Design for a Catball Game Device, of which the following is a specification, reference being had to the accompanying drawing, forming part thereof.

Figure 1 is a perspective view of the catball game device, showing my new design;

Figure 2 is a side elevation;
Figure 3 is a plan view; and
Figure 4 is an end view looking toward the right of Fig. 3.

I claim:

The ornamental design for a catball game device, as shown.

THOMAS R. SCHLITZ.
